US00D802736S

(12) **United States Design Patent** (10) Patent No.: **US D802,736 S**
(45) Date of Patent: **** Nov. 14, 2017**

(54) **FAN**

- (71) Applicant: **LG ELECTRONICS INC.**, Seoul (KR)
- (72) Inventors: **Joosang Kim**, Seoul (KR); **Sungkyong Han**, Seoul (KR); **Yunseo Jang**, Seoul (KR); **Sehwan Bae**, Seoul (KR)
- (73) Assignee: **LG ELECTRONICS INC.**, Seoul (KR)

(**) Term: **15 Years**

(21) Appl. No.: **35/501,537**

(22) Filed: **Mar. 11, 2016**

(80) **Hague Agreement Data**

Int. Filing Date: **Mar. 11, 2016**
Int. Reg. No.: **DM/089909**
Int. Reg. Date: **Mar. 11, 2016**
Int. Reg. Pub. Date: **Sep. 16, 2016**

(30) **Foreign Application Priority Data**

- Dec. 11, 2015 (KR) 30-2015-0063485
- (51) **LOC (10) Cl.** **23-04**
- (52) **U.S. Cl.** ..... **USPC D23/378**
- (58) **Field of Classification Search**
USPC D23/378, 379, 380, 381, 382, 383
CPC F04D 25/00; F04D 25/10; F04D 25/08;
F04D 25/105; F04D 25/166; F04D 17/04
